UNITED STATES PATENT OFFICE.

WILLIAM H. WILEY, OF HENDERSON, ASSIGNOR OF ONE-HALF TO J. ALLEN
MOORE, OF GREENSBOROUGH, MARYLAND.

FRUIT-DRIER.

SPECIFICATION forming part of Letters Patent No. 259,621, dated June 13, 1882.

Application filed March 20, 1882. (No model.)

To all whom it may concern:

Be it known that I, WILLIAM H. WILEY, of Henderson, in the county of Caroline, and in the State of Maryland, have invented certain new and useful Improvements in Fruit-Driers; and I do hereby declare that the following is a full, clear, and exact description thereof, reference being had to the accompanying drawings, making a part of this specification, in which—

Figure 1 is a perspective view of my improved apparatus, the casing being partly opened and broken away to show the operative mechanism. Fig. 2 is a central vertical section of the same upon a line parallel with the plane of motion of the crate-moving mechanism. Fig. 3 is a side elevation of one of the end plates of a swinging crate, and shows the means employed for connecting the same to or with its pivotal shaft. Fig. 4 is a like view of said apparatus in a line having a right angle to the section-line of Fig. 2. Fig. 5 is a perspective view, enlarged, of one of the pivotal bearings for the crate-moving chain, the parts being separated; and Fig. 6 is a like view of the same with said parts combined for use.

Letters of like name and kind refer to like parts in each of the figures.

The design of my invention is to enable fruit to be easily and quickly deprived of moisture and rendered fit for storage or transportation; and to this end it consists, principally, in the means employed for moving the fruit-crates through the drying-chamber, substantially as and for the purpose hereinafter specified.

It consists, further, in the means employed for insuring the relative positions of the fruit-crates, substantially as and for the purpose hereinafter shown.

It consists, further, in the means employed for lessening the friction of the operative mechanism, substantially as and for the purpose hereinafter set forth.

It consists, further, in the means employed for perfecting such fruit as may be imperfectly dried, substantially as and for the purpose hereinafter shown and described.

It consists, further, in the construction of the crates employed for the reception of fruit-

trays, substantially as and for the purpose 50 hereinafter shown.

It consists, finally, in the fruit-drier constructed and adapted to operate in the manner and for the purpose substantially as and for the purpose hereinafter set forth. 55

In the annexed drawings, A and A' represent the side walls of a casing which is substantially square in horizontal section, and has preferably a height equal to about twice its width. The upper end of said casing is enclosed by two outward and downward inclining covers, B, that are preferably hinged, between which is a raised portion, B', that has attached thereto or is connected with a flue, C. 60

Within the upper portion of the casing described is journaled horizontally a shaft, D, upon which, near the side walls, A, are secured two plates, E, that have each preferably the form in side elevation shown, and at each of its radial projections is provided with a semi-circular recess, e, the said recesses in each plate corresponding in relative position to the recesses of the opposite plate. 70

Supported upon and passing around the upper portions of the recessed plates E is a carrier 75 composed of a number of shafts, F, which are connected together at or near the ends by means of links G, that have each end pivoted to or upon one of said shafts. The length of each of said shafts is such as to permit it to extend between said plates with its ends resting within the recesses e, while the lengths of said links correspond to the distance in a direct line between two of said recesses, whereby when said plates are caused to revolve said shafts will 80 successively engage with the latter, as shown. There being but one set of plates, E—which plates, with their shaft D, operate as sprocket-wheels—it is necessary that that portion of the carrier below said wheels should be held 85 in position and prevented from lateral displacement, which result is secured by attaching to the inner face of each side A of the casing plates H, within each of which is formed a groove, h, that extends from near the upper 90 line of said wheels vertically down at one side to a point near the lower end of said casing, thence in a downward curve to the opposite 95

side, and thence upward again to a point corresponding to the upper end at the opposite side of said groove. The grooves *h* are located so as to receive the projecting ends of the shafts *F* and confine the same in position, and at their curved lower ends have a considerably increased width, in order to prevent obstruction to the carrier if from wear or from other causes said carrier should lengthen.

In order that friction and wear of the carrier may be prevented, the ends of the shafts *F* are each provided with a journal, *f*, upon which is journaled a roller, *I*, that is preferably secured in place by means of a screw, *f'*, which passes through a washer, *f''*, into the end of said journal. Each roller *I* has such diameter of its body as to enable it to fit into any of the recesses *e* of the plate *E*, and such length as to cause it to project beyond said plate and into the groove *h*, by which arrangement said roller furnishes a rolling bearing for its shaft *F* within said groove, and also within the recesses of said wheel. The portion of said roller *I* outside of said wheel *E* is preferably enlarged so as to form a shoulder, *i*, which engages with the outer face of the latter and insures the lateral position of said carrier while passing over said wheel.

Suspended from each shaft *F* is a crate, which, as seen in Figs. 2 and 3, is composed of two horizontally-grooved end plates, *K*, that are connected together by means of rods or bars *k*, which extend between their upper and lower ends. Said crates have such length as to enable them to swing freely between the links *G*, and, being journaled near their upper ends upon said shafts, maintain their position at all points. The grooves *k'* of the plates *K* have such dimensions as to enable each to receive one end of a fruit-tray, and as many trays may be placed in each crate as there are grooves in the same. Each plate *K* is provided near its upper end with a slot, *k''*, which extends from one edge laterally inward to the transverse center, and thence upward for a short distance, and permits said plate to be hooked on and suspended from a shaft, *F*, as seen in Fig. 2, after which the insertion of a vertical pin, *k'''*, beside said shaft and upon the side toward the open end of said slot securely locks said parts in position.

When in use each crate is filled with trays of fruit, and the carrier is moved so as to carry said crate upward and to bring the next lower crate into position for filling, and if the velocity and temperature of the air passing upward through the casing is properly regulated, by the time the crate has made the entire circuit after having been filled its fruit will have become cured and may be removed and replaced by fresh fruit.

Access to the interior of the casing for the purpose of filling or emptying the crates is had through a door, *A*², which is provided within one of the walls, *A'*, as seen in Fig. 1, while an inspection of the interior of said casing with

its contents may be made by raising the hinged cover *B*.

Should it be found, as is sometimes the case, that the fruit upon a tray is not thoroughly cured after the same has made a circuit of the casing, said tray is placed within a compartment, *L*, which is provided at the center of said casing, and to which access is had through a door, *A*³, that is provided in the wall *A*. The said chamber has sufficient width only to enable it to receive a tray, and within its sides is provided with horizontal grooves *a* for the reception of the edges of said trays.

The upper and lower ends of the chamber *L* are open, and within said lower end are hinged or pivoted two dampers or valves, *M*, which are arranged to swing inward and upward, as shown, so as to enable said opening to be partially or entirely closed to regulate the temperature within and the flow of air through said chamber.

Access to the interior of the casing for the purpose of removing or placing in position the rollers *I* is had through openings that are provided in each wall *A* and are inclosed by plates *N*. Through said openings the carrier can be repaired without rendering necessary its removal from said casing.

The carrier is moved by means of a sprocket-wheel, *O*, which is secured upon the projecting end of the shaft *D*, a pinion, *P*, that is secured upon a shaft which is journaled near the lower end of the casing, and is rotated by means of a hand-wheel, *Q*, and a chain, *R*, which passes around and engages with said sprocket-wheel and pinion. By rotating said hand-wheel its motion is transmitted through the mechanism described to said carrier, and the latter is caused to move steadily and with ease.

In consequence of the means employed for supporting and guiding the carrier far less friction results and materially less power is required to operate the same than would be possible were a set of sprocket-wheels employed at each end of the casing to support and guide the carrier, as has heretofore been the case, and I am enabled to handle with ease a quantity of fruit that would be impracticable to operate with were the construction such as last above described.

My construction also possesses marked advantages over the employment of a set of sprocket-wheels at each end of a vertical casing, as the lengthening and shortening of the carrier in consequence of changes of temperature and of wear render impracticable a proper tension around said wheels, and said carrier would at times be too tight and at other times too loose, while in case of my machine provision is made by the size of the lower portions of the grooves for variations in the length of the carrier, and its perfect freedom of motion is in no manner interfered with by such changes.

Having thus fully set forth the nature and merits of my invention, what I claim as new is—

1. As an improvement in fruit-driers, the combination, with a vertical casing, of an endless double chain or carrier supported wholly by and pendent from two combined carrying-wheels which are secured to and revolve with the same shaft within the upper portion of said casing; crates for trays of fruit, pivoted to and swinging upon said carrier; a groove at or within each side of said casing, adapted to receive the ends of the pivotal shafts of said crates and to guide and control the position of said carrier below said carrying-wheels; and means whereby the latter may be caused to rotate and to move said carrier longitudinally, substantially as and for the purpose specified.
2. The means employed for insuring the relative positions of and for moving the fruit-crates through the vertical drying-chamber, consisting of the shafts F, having pivoted thereon said crates, the links G, connecting together said shafts, the wheels E, secured upon the same shaft D and provided with peripheral recesses e, and the grooves h, adapted to receive the ends of said pivotal shafts F and to guide and control the position of the endless carrier in its passage from said wheels downward through the lower end of said drying-chamber and upward again to said wheels, substantially as and for the purpose shown.
3. In combination with the shafts F, wheels E, and groove h, the rollers I, journaled upon the ends of said shaft and having their outer ends enlarged to form shoulders i, substantially as and for the purpose set forth.
4. In a fruit-drier having means for moving the fruit through a vertical casing, a central chamber provided with valves for regulating the temperature and currents of air, and adapted to receive and contain trays of fruit, substantially as and for the purpose shown and described.
5. The crates for containing trays of fruit, consisting of the plates K, provided with the grooves k', slots k², and pins k³, and combined by means of the connecting-rods k, substantially as and for the purpose shown.
6. The hereinbefore-described fruit-drier, in which is combined a vertical casing, an endless carrier provided with swinging crates, that passes over and is wholly supported by a pair of combined carrier-wheels journaled by the same shaft within the upper portion of said casing, grooves that receive the edges of and guide said carrier while passing through the lower portion of said casing, and mechanism, substantially as described, whereby said parts are caused to operate in the manner and for the purpose substantially as set forth.

In testimony that I claim the foregoing I have hereunto set my hand this 1st day of March, 1882.
